UNITED STATES PATENT OFFICE.

THOMAS P. BACON, OF OAKLAND, CALIFORNIA.

ROBE-LOCK.

1,072,559.

Specification of Letters Patent. Patented Sept. 9, 1913.

Application filed May 14, 1912. Serial No. 697,150.

To all whom it may concern:

Be it known that I, THOMAS P. BACON, a citizen of the United States, residing at Oakland, in the county of Alameda and State of California, have invented new and useful Improvements in Robe-Locks, of which the following is a specification.

This invention relates to a lock, and particularly pertains to a pad-lock for locking 10 lap-robés and the like to supporting rails.

It is the object of this invention to provide a lock which is especially adapted for use in locking lap-robés and similar articles to suitable supports so as to prevent their 15 being stolen, and to produce a lock so constructed that it can be securely clamped to articles of various thicknesses and locked thereon.

The purpose of this invention is to provide 20 a pad-lock having a reciprocable bolt so arranged that it may be manually advanced in the lock casing toward a fixed keeper carried by the casing and to provide key controlled means for locking the bolt 25 against retraction in various positions.

The invention resides primarily in a substantially U-shaped rigid clasp provided with a lock having a sliding bolt operating 30 across the opening of the clasp and operating jaw fashion with the end of the clasp opposite the lock, and means for locking the bolt against retraction in various positions.

The invention further consists of the parts and the construction and combination 35 of parts as hereinafter more fully described and claimed, having reference to the accompanying drawings, in which—

Figure 1 is a side view of the invention with parts broken away, showing it as applied 40 in locking a lap-robe to a rail. Fig. 2 is a perspective view.

In the drawings A represents the lock casing which may be of any suitable construction and which is here shown as 45 formed with a pair of face plates spaced apart and joined together at their edges. Slidably mounted between the two face plates of the lock casing is a reciprocable bolt 2, here shown as rectangular in cross- 50 section, on the upper face of which is formed a series of ratchet teeth 3. The bolt 2 is designed to extend some distance beyond the edges of the lock casing A and is fitted with a handhold 4 on one end, by 55 which it may be moved longitudinally in either direction within the lock casing A, so

as to dispose its inner end in any desired position in relation to a keeper 5 formed on one end of a U-shaped clasp 6, to the other end of which the lock casing A is connected 60 or formed integral therewith. The keeper 5 is positioned opposite the inner end of the bolt 2 and substantially at right angles to the adjacent leg of the clasp member 6, and is formed with V-shaped notches or 65 teeth 7 on its face, which are designed to receive the correspondingly shaped complementary teeth 8, formed on the inner end of the bolt 2. The keeper 5 is positioned some distance from the lock casing A, while the 70 clasp 6, on which the keeper 5 is mounted, is arched so as to form a hook which is designed to be placed over or around the members to be locked together, as will later be described. 75

The bolt 2 is designed to be engaged with the keeper 5 and locked against retraction so as to inclose the members it is desired to lock together within the space formed within the clasp 6 and the bolt 2. The article to be 80 fastened by the lock may, however, be clamped between the inner end of the bolt 2 and the keeper 5, where the occasion requires; the bolt 2 being locked against retraction in any desired position by means of 85 a spring pressed locking pawl 9 mounted within the lock casing A, and positioned to normally engage the ratchet teeth 3 on the bolt 2, as shown in Fig. 1. The pawl 9 is here shown as being in the form of a lever, 90 pivotally mounted on a pin 10 carried by the side plates of the lock casing A, the lower end of which lever is held in normal engagement with the ratchet teeth 3 by means of a plate spring 11 mounted on the 95 end of the lock casing A, bearing against the underside of the upper end of the pawl 9 which extends upwardly at an incline.

The pawl 9 is designed to be thrown out of engagement with the ratchet teeth 3 to 100 permit of a free reciprocation of the bolt 2 by means of a key 12 of any suitable description, the bit of which is inserted through a keyhole 13 formed in the lock casing A, and is arranged to engage or bear 105 against the upper portion of the pawl 9 when the key is turned, so as to rock the pawl in opposition to the spring 11, and thereby withdraw its lower end out of engagement with the ratchet teeth 3. When 110 this is done, the bolt 2 may be freely retracted or advanced. By this construction

the key 12 may be inserted and withdrawn from the lock casing irrespective of the position of the bolt 2; the pawl 9 acting on its release to immediately engage the ratchet teeth 3.

From the foregoing it will be seen that when the bolt 2 is in its retracted position and the spring pressed pawl 9 is engaged therewith, the bolt 2 may be advanced any 10 desired degree by means of the handhold 4; the pawl 9 engaging the ratchet teeth 3 in such manner as to lock it against retraction in any position.

In the operation of the invention as applied to locking a lap-robe 14 or the like, the latter is thrown over a rail 15 in the usual manner, as shown in Fig. 1. The bolt 2 being retracted admits of the U-shaped clasp 6 being positioned over the rail 15 so as to 20 dispose the keeper 5 on the one side of the robe and the inner end of the bolt on the opposite side thereof. The bolt 2 is now advanced so as to clamp the two folds of the lap-robe 14 between the end of the bolt 2 and the keeper 5; the spring pressed pawl 9 locking the bolt 2 against retraction. This being done the lap-robe 14 is securely locked 25 upon the bar 15 against removal.

It is obvious that this lock is equally applicable for use in any instance where it is 30 desired to connect two members together, by inclosing the members within the space formed within the U-shaped clasp 6 and the sliding bolt 2.

Having thus described my invention, what 35 I claim and desire to secure by Letters Patent, is—

A robe lock comprising a U-shaped member, a lock casing attached to one end of said U-shaped member, tumblers carried by said lock casing, a holding jaw formed upon the other end of said U-shaped member, a bolt passing entirely through said lock casing, a holding face formed upon the end of said bolt, said face being adapted to coöperate 40 with said holding jaw, a hand hold formed upon the other end of said bolt, and ratchet teeth upon said bolt.

In testimony whereof I have hereunto set my hand in the presence of two subscribing 50 witnesses.

THOMAS P. BACON.
